UNITED STATES PATENT OFFICE.

CHARLES S. WHITWORTH, OF CEDAR FALLS, IOWA.

GATE-HANGING MEANS.

1,119,558.

Specification of Letters Patent.

Patented Dec. 1, 1914.

Application filed March 9, 1914. Serial No. 823,498.

To all whom it may concern:

Be it known that I, CHARLES S. WHITWORTH, a citizen of the United States of America, and a resident of Cedar Falls, 5 Blackhawk county, Iowa, have invented certain new and useful Improvements in Gate-Hanging Means, of which the following is a specification.

My invention relates to improvements in 10 gate-hanging means, and the object of my improvement is to adapt the hinges of a gate, or more particularly, of a gate of flexible construction, so that the rear stile of the gate may be supported for vertical 15 adjustment, while yet being hinged to horizontally swing from its support. This object I have accomplished by the means which are hereinafter described and claimed, and which are illustrated in the accompanying 20 drawings, in which:

Figure 1 is a side elevation of part of a flexible gate, including the rear stile in vertical section, and the gate supports being also shown in vertical section. Fig. 2 is a 25 perspective view of the orificed engaging body for the upper part of the rear stile. Fig. 3 is an under plan view of said orificed body, and Fig. 4 is a variation of said body in perspective. Fig. 5 is a reduced side elevation of the flexible gate equipped with my 30 said improvements.

Similar numerals of reference denote corresponding parts throughout the several views.

The flexible gate shown in said Fig. 5 is 35 of the well known type comprising front and rear stiles 18 and 1, respectively, connected by means of spaced horizontal tubular bars 8 and 12 connected thereto by means 40 of pivot bolts 9 and 13. The stiles, however, are formed of U-shaped channel bars with their longitudinal openings placed oppositely and directed inwardly, and a plurality of hook-bolts 7 are inserted one above another in the rear stile 1 through openings 45 therein, and secured thereto by means of the nuts 27. A plurality of connecting wires 17 are connected between said hook-bolts and the head stile 18, as shown. A pair of 50 vertical bars 28 are placed on opposite sides of said gate over said wires, and the tubes 8 and 12 and secured together by means of bolts 29 so as to hold said parts in place, while yet permitting pivotal movement 55 thereof. In order to keep the said stiles in an adjusted position, I have employed a

pair of wires 24, whose forward ends are connected to a clip 26, and whose rear ends are secured to springs 25, which latter are secured to the upper end of the stile 1. The 60 clip 26 may be adjusted along the head stile 18, and the springs 25 then yieldingly hold the head stile in an adjusted frictional engagement with the clip. The gate has in its head stile, the movable bolt 19, which is 65 adapted to be engaged with a catch 20 on the head post 30, and swinging members 21 are mounted to rock on said head post and permit the head stile to pass between them by lifting them first, then dropping down when 70 the stile is between them, to hold the stile in that position.

The numeral 14 denotes a fixed support or post which is orificed to receive the eye-bolts 2 and 10 spaced apart above each other and 75 kept in alinement by means of nuts 3 and 11. The stile 1 is seated slidably within the eyes 2 and 10 and is held in an adjusted position on the uppermost bracket or eye-bolt 2 by the following parts.

Referring now to Figs. 1 to 3, inclusive, the numeral 4 denotes a disk-shaped body having an opening 6 curved at one end and squared at the opposite end and adapted to fittingly and slidably seat the U-shaped rear 85 stile 1. Said disk 4 has a depending integral part 5 which is adapted to be seated inside of the orifice of the eye-bolt 2 and has its outer side curved to fit said eye, and to prevent its being withdrawn therefrom when 90 the stile 1 is passed through both the eye-bolt and the eye 4. The body 4 is thus adapted to rock on the eye 2, but the stile 1 is prevented from rocking in the orifice of the body 4, although vertically slidable 95 therethrough. The stile 1 is provided with a number of orifices 15, in any one of which a pin 16, suspended on a chain 23 may be inserted adjustably above the body 4 when said stile has been elevated sufficiently. It will be 100 seen that the above arrangement of the parts permits the gate to be freely swung horizontally at any adjusted vertical position. The gate may thus be adjusted vertically away from the ground at a desired distance, and 105 yet, is held rigidly in place when being swung to and fro.

The use of the U-shaped-channel bars for the stiles is both useful and convenient, not only in assembling the gate because of the 110 convenience of securing the hook-bolts 7 thereto, but also, because of the great

strength of such bars which receive the thrust of the suspending parts of the gate. The shape of the said channel bars lends itself favorably to my important method of 5 adjustably mounting the rear stile, and supporting it at desired distances from the ground. However, I do not confine myself to a U-shaped channel bar stile 1, for other forms may be used with my hanging-means.

10 For instance, in Fig. 4 is shown a variation of the orificed body 4, in which the forward part only is retained with its depending part 5. These parts will remain secured to the eye-bolt 2 when the stile 1 is inserted, and in 15 that case, the pin 16 rests upon the eye 2.

Having described my invention, what I claim as new, and desire to secure by Letters Patent, is:

1. Gate-hanging means, comprising in 20 combination, a gate-stile of U-shaped section, a fixed support, brackets on said support having alined orifices to receive said stile slidably, a body removably supported on the uppermost bracket, having a fitting orifice to receive said stile slidably, and having a depending portion passed rotatably through the orifice of the supporting bracket and engaging the squared edges of said stile, and means adjustably secured upon the stile 25 for adjustably supporting said stile upon said orificed body.

2. Gate-hanging means, comprising in combination, a gate-stile of U-shaped section, a fixed support, brackets on said support having circular alined orifices to receive 30

said stile slidably, a body removably supported on the uppermost bracket, having a fitting orifice to receive said stile, and having a depending portion passed rotatably through the orifice of the supporting bracket 40 and engaging the squared edges of said stile and the abutting curved edge of said bracket, said stile having a plurality of transverse holes one above another, and a pin adapted for insertion into any of the holes to adjustably support the stile upon the said stile-fitting orificed body.

3. Gate-hanging means, comprising in combination, a gate-stile of U-shaped section, a fixed support, annular brackets on 50 said support having alined orifices to receive said stile slidably, a body removably supported on one of the brackets having an orifice shaped to fit about said stile slidably, said body having a depending portion seated rotatably in the orifice of the bracket and having one side squared to fit the squared edges of the stile and its opposite part annularly grooved to engage and fit the inner wall of the bracket to be thereby locked 55 against longitudinal displacement when said parts are assembled, and means for supporting said stile upon said body.

Signed at Cedar Falls, Ia., this 20th day of Feb., 1914.

CHARLES S. WHITWORTH.
